UNITED STATES PATENT OFFICE.

FRANK WELLINGTON WARDWELL, JR., OF CLEVELAND, OHIO.

MACHINE FOR SHARPENING PLANER-BLADES.

1,172,183.

Specification of Letters Patent.

Patented Feb. 15, 1916.

Application filed April 20, 1914. Serial No. 833,301.

To all whom it may concern:

Be it known that I, FRANK WELLINGTON WARDWELL, Jr., citizen of the United States, residing at Cleveland, in the county of Cuyahoga and State of Ohio, have invented certain new and useful Improvements in Machines for Sharpening Planer-Blades, of which the following is a specification.

This invention consists in a machine for sharpening planer blades, all substantially as shown and described and particularly pointed out in the claims.

In the accompanying drawings, Figure 1 is a perspective view of the machine complete. Fig. 2 is a sectional plan view with a portion of the base broken away and corresponding to a horizontal line axially through the two horizontal supporting tubes. Fig. 3 is a detail of the immediate 20 grinding attachment showing the same in elevation and sectioned axially through the grinder and the axis thereof. Fig. 4 is an end elevation of the machine, looking in from the left of Fig. 1. Fig. 5 is a sectional view centrally lengthwise of the near supporting tube in Fig. 1.

The grinder or sharpener for the planer or other blade to be sharpened is indicated by G, and the mechanism shown is intended 30 to be removably mounted on the planer bed with the grinder in adjustable working relations with the planer blades so that perfectly true sharpening results may be obtained continuously from end to end of each 35 single blade or the several blades on a single cutter head. To these several ends grinder G is carried by a vertically disposed shaft S in direct actuating relations with an electric motor M, and said parts are supported together on or by means of a head H mounted 40 to travel or slide on the guide bar or plate P. The said bar or plate is supported at or near its ends on the two supporting tubes D and D' which are horizontally mounted 45 upon the two tubular standards or posts C by means of brackets b slidably mounted on said standards. The standards C are rigidly 50 socketed in the base B and serve as rigid guide members for the said brackets in any vertical adjustment of said brackets and the 55 tubes D and D' thereon. The brackets b are right angled parts and have a clamped relation to both the standards C and the cross pipes or tubes D and D' less the fact that 60 said brackets are slidably mounted on said standards under actuation through the cross

connecting plate or member F which rigidly unites said brackets b and has nuts n fixed on the face thereof for the pair of screws m. A top plate L connects the upper ends of the said standards and has bearings 2 on its bottom for the screws m and a central bearing for the operating shaft M. The said shaft also passes through a lug n' on plate F and occupies the central of three 65 bearings 2' on the base B, and other two bearings being occupied by the ends of the adjusting screws m. The parts B, C and L practically constitute the frame of the machine and all the other parts are supported 70 thereon or therefrom and are movable in respect thereto. Each of the said adjusting screws has a gear 3 on its lower extremity in mesh with a pinion 4 on shaft N beneath base B, and the said gears 3 are alike 75 in size and function and serve to give primary or initial position and relation to the grinder G. Such position or adjustment of the parts is accomplished by raising or lowering the brackets b and the carrying tubes 80 D and D' on the standards C. Finer adjustment of the said grinder is more local and comprises means for setting the grinder or the bar carrying the same so that the grinder will work accurately on the same 85 level its entire length of travel and from blade to blade on the planer. Thus, the grinder G is carried by the two-part shaft S driven by the motor M and supported in a vertically disposed tubular bearing 5 rigid 90 with bracket H and having a length nearly equal to the length of shaft S so as to steady the same. The lower portion or section of said shaft is, however, allowed a slight measure of axial play under domination of the 95 spring 7, which has uniform tension and serves to hold the grinder down to effective work. The said shaft S is therefore made in two parts interlocked, one of which is fixed in the grinder and the other in the 100 motor and the joint provides for positive actuation and is located beneath said spring.

In the finer adjustments of the grinder above referred to I have in mind the fixed relation of guide-bar or plate P in respect 105 to transverse tube or pipe D' and such adjustment of said plate upon or in respect to the pipe or tube D as will afford a limited adjustment thereon for leveling purposes. This is accomplished by the means seen in 110 Fig. 5, wherein the said plate is shown as secured to the tube D by a tie rod extending

lengthwise through the tube and threaded into a stud 9 which has a head bearing against the outside of the said plate. A thimble 10 is placed on the said stud and a box 12 threaded 5 on the end of the tube D overlaps said thimble and set screws 14, top and bottom, are inserted through said box and bear on said thimble and serve to make such limited adjustment as the said plate may require to 10 fix its working level. The exact level at any time can be read by the index finger 15 on the indices 16 on box 12, see Figs. 3 and 4. Plate P is rigidly affixed to tube D' and this tube turns in its bracket b and permits 15 the said plate to be raised or lowered at its connecting point with the other tube D. The head H which carries the motor on plate P has ribs 17 or their equivalent engaging the edges of said plate. In machines of this 20 general kind absolute steadiness and uniformity in the work is of the first importance, and any tremor or chattering or yielding in the grinding parts other than provided for is detrimental. The present machine is therefore built rigid and strong and 25 the different parts all particularly related as shown so as to insure absolute stability of structure and uniformity in operation. The slight adjustments through box 12, and 30 axial yield in the grinder shaft conserve the operations in these particulars, while the primary adjustment through the two screws m fix the position of the grinder G in the main. A hand crank h on actuating shaft 35 N serves to turn the same and to rotate the screws m simultaneously. Bed plate B is adapted to be fixed in working position upon the planer by bolts entered through the several slots 18 therein. The head H 40 which carries the electric motor and the grinder is adapted to travel or slide on the guide bar P, and a hand grip 19 or any suitable means may be employed to move said parts upon said bar.

45 What I claim is:

1. A machine for sharpening planer blades having a frame with two standards, a bracket slideable on each standard and rigidly connected, horizontally disposed 50 supports secured in said brackets, a guide-bar fixed on the inner ends of said supports, two adjusting screws supported between said standards and in adjusting relations with

said brackets, and an actuating shaft intermediate said screws and geared therewith to 55 rotate the same.

2. In a machine as described, the combination of the upright frame having a base and a pair of standards fixed therein and a rigid cross connection at the top of said standards, 60 a bracket slidably mounted on each standard and cross piece connecting the same, and horizontally disposed tubes mounted in said brackets, in combination with means to raise and lower said brackets and tubes comprising a pair of screws supported between said standards and having fixed nuts in the plate connecting the said brackets and means to rotate said screws simultaneously. 65

3. In a machine for sharpening planer 70 blades, a horizontally disposed guide-bar having a fixed support at one end and an adjustable support at the other end adapted to fix said bar at different levels, in combination with a motor and a sharpening device operatively connected and means supporting the same in a traveling relation on 75 said bar.

4. In a machine as described, a set of horizontally disposed supports, a guide bar 80 pivotally supported at one end by one of said supports and means connected with the other support to level said bar, said means comprising a stud engaging said bar against the end of the said support, a screw to tighten 85 the said stud on said bar and leveling screws adapted to fix the horizontal position of the bar.

5. In a machine as described, a pair of laterally disposed supports and a guide bar 90 mounted on the free ends of said supports, in combination with leveling means at one end of said bar comprising a screw rod through the corresponding support and a stud having a head bearing on said bar engaged by said screw, a thimble on the neck of said stud inside said bar, a box on said support and leveling screws top and bottom through said box having bearings on said thimble. 95

In testimony whereof I affix my signature in presence of two witnesses.

FRANK WELLINGTON WARDWELL, JR.
